INTERNAL COMBUSTION ENGINE

Charles H. Thompson, Sacramento, Calif.

Application March 17, 1936, Serial No. 69,392

2 Claims. (Cl. 123—44)

This invention relates to internal combustion engines and more particularly to internal combustion engines of the rotary type.

An object of the invention is to simplify the structure of rotary internal combustion engines and at the same time to increase the power thereof to the end that maximum power may be obtained with minimum fuel consumption.

The invention together with its objects and advantages will be best understood from a study of the following description taken in connection with the accompanying drawings wherein:

Figure 1 is a sectional view through the engine.

Figure 2 is a detail elevational view showing the manner of mounting on the engine an injector cylinder.

Figure 3 is an enlarged detail sectional view through the injector cylinder and further illustrating the means for reciprocating the piston forming part of the injector.

Figure 4 is a fragmentary plan view showing the means for reciprocating the injector piston.

Figure 5 is an elevational view taken substantially at right angles to Figure 3 and viewing the same from the left of Figure 3.

Figure 6 is a fragmentary plan view of the rim of the rotor.

Figure 7 is an enlarged detail sectional view taken at right angles to Figure 1.

Figure 8 is a fragmentary elevational view from the driving end or side of the rotor.

Figure 9 is a fragmentary perspective view illustrating certain details hereinafter more fully referred to.

Referring to the drawings by reference numerals it will be seen that the internal combustion engine comprises an outer band divided into a pair of complementary sections 5, 6, which at their ends are provided with lugs 7 through the medium of which and bolts 8 the sections 5 and 6 are connected together and secured to the side members 9 of any suitable stationary supporting frame structure.

Revolute within the confines of the outer rim is a rotor which includes a crank case in the form of a hub 10 from which radiates cylinders 11. While any number of cylinders may be employed in the present instance there have been illustrated but four such cylinders.

At their outer ends the cylinders 11 are integral with a rim or band 12 that has a rotative fit within the outer band.

As shown in Figure 7 the sections 5 and 6 of the outer band and the sections of the rim 12 between

the cylinders 11 are complementarily ribbed and grooved as indicated generally at 13.

For one side of the casing 10 there is provided a cover plate 14 secured to the member 10 by bolts or the like 15.

At the center thereof the plate 14 is provided with a formation 16 from the center of which extends the main drive shaft 17 that is adapted to be connected in any suitable manner with the work that is to be driven.

Shaft 17 is journaled in a suitable bearing 18 provided therefor on one of the frame members 9a that connect the aforementioned frames 9 at the ends of the latter. Bearing 18 as shown is suitably provided at 19 for a lubricant fitting and also with an oil ring 20.

Secured to the opposite end of the hub or casing 10 through the medium of bolts 21 is an annular plate 22 in which is fitted a babbitt bearing 23. At its inner end the bearing 23 is provided with a flange 24 that has an edge portion thereof clamped between the plate 22 and the adjacent end of the hub or crank case 10.

The reference numeral 25 indicates one end of an axle that extends through a bearing 26 and on the end of the axle 25 is a disk 27 which is accommodated within the bushing 23 as shown. Secured to this disk 27 as at 28 and disposed against the outer face of the annular plate 22 is an oil retainer plate 29. Thus in this manner the rotor is supported to rotate about the axle 25 and its disk 27 has an axis.

Disk 27 is provided with any desired number of concentrically arranged openings 30 into a selected one of which is placed one end of an eccentric pin 31.

Suitably connected with the free end of the pin 31 is one end of connecting rods 32 provided for the piston 33 mounted to reciprocate within the cylinders 11. Obviously the desired compression is obtained by placing the pin 31 in the proper socket or opening 30 of disk 27. It will also be apparent that as the rotor revolves pistons 33 are constrained to reciprocate within the cylinders 11 and as the cylinders fire in proper sequence the rotor will be caused to revolve as is thought apparent.

Provided in the fixed outer ring section 5 is a port 34 into alignment with which and the intake port 35 provided in the rim 12 the cylinders 11 successively move for charging the cylinders 11 with fuel.

For charging purposes there is provided an injector which includes a cylinder 36 suitably mounted on the ring section 5 and adapted to be

connected at one end 37 with a carburetor (not shown).

Inwardly from the end 37 cylinder 36 is provided with a guide bar 38 through which works a valve stem 39 provided for a valve 40 engageable with a seat 41 fixed within the casing 36 at the side of the guide 38 farthest remote from the end 37 of the cylinder.

A spring 42 serves to yieldably retain the valve disk 40 engaged with its seat 41.

Mounted for reciprocation within the cylinder 36 at the side of the seat 41 opposite to the guide 38 is a piston 43 which serves to draw fuel into the cylinder 36 from the carburetor and, with valve 40 open, pass the valve seat 41 to subsequently force the fuel under pressure through the port 45, and through port 34 and the port 35 aligned with the port 34 into the proper cylinder.

For reciprocating the piston 43 as the rotor 20 revolves there is provided on the free end of the piston rod 46 an arm 47 formed at one end with a hook 48.

Secured to one side edge of the rim 12 of the rotor is a continuous cam ring which at intervals 25 has formed integrally therewith attaching brackets 48 bolted or otherwise secured at 49 to the rim 12. The cam ring is corrugated to provide in alternation cam hollows 50 and cam humps 51, and the hook 48 engages the cam ring in a 30 manner clearly shown in Figures 3 and 7 so that as the rotor revolves the cam ring so engages the hook 48 that, through the medium of the cam humps 51 and the cam hollows 50, the piston 43 will be caused to reciprocate for drawing fuel into 35 the cylinder 36 past the valve 40 and subsequently forcing the fuel from the cylinder 36 into the successive cylinders 11.

The section 6 of the stationary ring is provided 40 with a single exhaust port 51 and an exhaust manifold 52 is suitably secured to the ring section 6 as shown in Figure 1. It will thus be seen that as each cylinder 11 moves into alignment with port 51 the burnt gases will exhaust therefrom to be carried off by the exhaust conduit 52.

For each cylinder 11 there is also provided a suitable breather cap 53.

Also in accordance with the present invention there is disposed on the plate 14 about the formation 16 a ring 54 of fiber or other suitable dielectric material and embedded within the ring at

intervals are contact elements 55 for use as a part of the ignition system.

Also, the rim section 5 at a suitable point there-of will be provided with a spark plug hole 56 to accommodate the spark plug 57 for igniting the 5 compressed charges in the successive cylinders.

For the casing 10 there is also provided on the rim section 5 a suitable valve controlled vent assembly 58.

Also for cleaning out the cylinders there is 10 provided in the rim section 6 an opening 59 with which the cylinders 11 are caused to successively align and extending from the opening 59 is a conduit 60 through which air under pressure or the like may be forced for use in cleaning out the 15 cylinders.

For lubricating the contiguous faces of the outer fixed ring and the rim 12 through the medium of the oil within the casing 10 there are provided oil conduit pipes 61 that extend from 20 the casing 10 to the rim 12 and these pipes are provided with suitable valves 62 as shown.

Having thus described the invention, what is claimed as new is:

1. A fuel injector for rotary internal combustion engines comprising an injector casing mounted on a stationary part of the engine, a cylinder in one end of the casing having a discharge port therein, said injector cylinder also having a longitudinally aligned end adapted to be connected 25 with a source of fuel supply and a piston operatively mounted within the injector cylinder for drawing fuel from said supply and forcing fuel under pressure through said discharge port, said injector casing having a guide member adjacent 30 the end thereof connected with said source of fuel supply, a valve seat in the injector casing inwardly of the guide, a valve engageable with said seat and having a stem working through said guide and a spring engaged with said stem 40 for yieldably urging said valve in engagement with said seat, said seat being disposed between said system and said valve guide.

2. Means for actuating the piston of a fuel injector for rotary internal combustion engines 45 comprising a rod extending from the piston, a hook member having a shank secured to the free end of said rod and means having wiping contact with the hook for reciprocally actuating the piston,

CHARLES H. THOMPSON.
